(57) **CLAIM**

I claim the ornamental design for a flexible ankle strap with hook-and-loop fasteners, phone/pager pocket with snaps and security strap, and zippered cash/credit card pocket, as shown and described.

DESCRIPTION

FIG. 1 is a perspective view of a flexible ankle strap with hook-and-loop fasteners, phone/pager pocket with snaps and security strap, and zippered cash/credit card pocket showing my new design;

FIG. 2 is a right side elevational view thereof;

FIG. 3 is a left side elevational view thereof;

FIG. 4 is a front elevational view thereof;

FIG. 5 is a top plan view thereof;

FIG. 6 is a bottom plan view thereof;

FIG. 7 is a rear elevational view thereof;

FIG. 8 is a cross-sectional view taken along line 8—8 of FIG. 1; and,

FIG. 9 is a perspective view showing the flexible ankle strap with hook-and-loop fasteners, phone/pager pocket with snaps and security strap, and zippered cash/credit card pocket in use; the broken lines depict environmental structure for illustrative purposes only and form no part of the claimed design.
